SELF-LOADING BOAT CARRIER
Wayne K. Morrison, 1334 Grand Ave.,
Oroville, Calif. 95965
Filed Oct. 20, 1965, Ser. No. 498,348
5 Claims. (Cl. 214—450)

The present invention relates to a new and improved hoisting apparatus for a boat carrier, and more particularly relates to a frame for a boat carrier that is constructed of industrial steel tubing, or other suitable material, and mechanical components, all of which provide a boat carrier that is adapted for use as a carriage for boats on a pick-up truck, or an automobile.

An object of the invention, therefore, is to provide a boat carrier which facilitates tricing the boat onto the boat carrier arrangement with a minimum of effort and ease of operation of the several mechanical components of the frame and boat carrier.

A further object of the invention is to provide a unique self-loading boat carrier having the advantages and features provided by the simple construction and ease in operation of the combined parts.

The above and other objects and advantages of the invention will become apparent upon full consideration of the following detailed description and accompanying drawings in which:

FIG. 1 is a side elevation view of a pick-up truck having the boat carrier of the invention, and in which a boat is disposed thereon;

FIG. 2 is a rear and side perspective view of the manner in which the apparatus is used to introduce a boat onto the boat carrier in accordance with the preferred embodiment of the invention;

FIG. 3 shows a roof-mounted pulley mechanism used to allow the support bar of the boat carrier to ride thereon;

FIG. 4 shows the manner in which the mechanism is adaptable for use with a coupe or sedan type automobile; and

FIG. 5 shows a plan elevation view of the boat carrier shown in FIG. 4, in which part of the automobile is shown in dotted line.

Referring now to the drawings, there is shown in FIGS. 1 and 2, a pick-up truck 10, a Y-frame comprising two upper arms 14, 14, and a lower extension or arm 16, and in which the ends of the upper arms 14, 14 are provided with hinge means 18, 18. At the free end of arm 16, there are mounted opposing extension arms 20, 22, and on the ends thereof are mounted pulleys 24, 26 for a cable 28 to pass thereover, as shown by the arrows 30, 32, 34, 36; and which is wound up upon the winch 40 as it may be turned by the crank arm 24 in the manner shown by the arrow 44. The winch 40 is mounted centrally of the Y-frame and beneath it so that a boat 50 upon being engaged by a hook 52 may be drawn upon the Y-frame, shown in FIG. 2, until it is stowed in the position shown in FIG. 1. The cable 28 not only passes from the hook 52 over the pulley 24 and pulley 26, but also over the pulley 60 and then back over a pulley 62 which is mounted centrally of a roof-mounted pulley mechanism 64 which comprises each of two arms 66, 66, in which their end members are hooked about to form hooks 68, 68 which may be engaged to the molding about a cab of the truck 10. Turn buckles or bolt mechanisms 70, 70 are adapted to secure the pulley mounting mechanism 64 securely in place so that the pulley 62 is firmly mounted upon the cab of the truck 10. From a U-shaped bracket 72, as shown in FIG. 3, there is mounted a large pulley or roller 74 for the leg 16 of

2

the Y-frame to roll upon as it is displaced from either the position of FIG. 1 to that of FIG. 2, and reversely. The cable then passes from pulley 62 onto the winch 40, as has been described above. On the upper end of the Y-frame, such as on the arms 14, 14, there are provided glides 80, 80 to assist in mounting the boat upon the Y-frame and into its stowed position as shown in FIG. 1. A roller 82 provides rolling action between the keel of the boat and the Y-frame, and it is supported from a transverse member connecting the hinges 18, 18 and the upper ends of the Y-frame 12.

The pulley 74 may also be called a frame tongue roller, since it allows the Y-frame 12 to roll over it, as shown. The extension or arm 16 extends to terminate at the pulley 82, which is transversely supported by a rod 90, which is connected to the hinge means 18, 18, each of the hinge means being supported from the truck by a swinging rod 92, 92. The swinging rods or hinged posts 92, 92 are hingedly engaged by pivots 94, 94, to the truck 10. The steel or iron car-top clamps of mechanism 64 are supported by foam rubber pads 96, 96 from the roof of the cab of the truck 10. A boat snubbing post 100 may be provided on the extension or arm 16 for supporting the boat from movement in a forward direction.

The frame of the carrier may be constructed of industrial steel tubing and other suitable material, and many parts such as the winch, pulleys and rollers are available from stock and may be arranged in accordance with the invention.

In FIGS. 4 and 5, there is shown a similar embodiment with similar reference numerals, but wherein keel rollers 106, 106 are provided in addition to the pulley or keel roller 82 provided at the rear end of the boat carrier.

FIGS. 4 and 5 show an automobile 110 in which a similar type of boat carrier having horizontal members forming the Y-shape construction including the extension or arm 16, and two upper arms 14, 14, glides 80, a boat snubbing post 100, the pulleys as shown, the keel rollers, is shown and is mounted similarly to function as has been described in connection with the pick-up truck 10. However, there is mounted on the forward portion of the opposing extension arm 20 a winch 114 for working the boat cable upon it, as has been described in connection with FIGS. 1 and 2. The crank arm 116 for the winch 114 is mounted at the end of a shaft 118, and in this way ease in operation of the winch 114 is accomplished.

Also shown in FIG. 5 and indirectly illustrated in FIGS. 1-4, is a set of web straps 120, 120 provided to anchor the pulley mechanism 64 onto the roof of the automobile or other vehicle, as shown.

It is seen by the illustrations and description of the mechanism of the invention that the boat carrier has the advantage of ease in construction and operation, and is substantially sturdy for achieving the objects and advantages of the invention.

Additional embodiments of the invention in this specification will occur to others and therefore it is intended that the scope of the invention be limited only by the appended claims and not by the embodiments described hereinabove. Accordingly reference should be made to the following claims in determining the full scope of the invention.

65 What is claimed is:

1. A self-loading boat carrier comprising a Y-frame having a hinge at the upper free ends of the Y-frame and opposing extension arms at the other ends thereof, a pulley mounted on one of the opposing extension arms, 60 a pair of hinged posts one end of which is adapted to be hingedly mounted from a frame portion of the automobile or truck, and the other end connected to the

free ends of the Y-frame, a winch and crank arm mounted from said Y-frame, a series of keel rollers mounted along the mid-portion of said Y-frame, and a roof-mounted pulley mechanism for the Y-frame to engage in rolling contact, a boat snubbing post being disposed on the lower portion of said Y-frame, and said roof-mounted pulley mechanism being clamped upon the roof of said automobile or truck by a set of web straps to anchor it thereto, said roof-mounted pulley mechanism having a pulley being centrally mounted on said roof and in alignment with said pulleys of said opposing extension arms and said winch so that a cable provided on said winch and said pulleys is reeled therebetween.

2. The invention according to claim 1 wherein said pair of free arms of the Y-frame are provided with a set of glides to assist the boat being unloaded onto the boat carrier.

3. The invention according to claim 2 wherein a foam

rubber pad is disposed beneath the roof-mounted pulley mechanism.

4. The invention according to claim 1 wherein the winch and crank arm are mounted from beneath a mid-portion of the Y-frame.

5. The invention according to claim 1 wherein said crank arm is mounted from an extended shaft member.
